US00D967554S

(12) **United States Design Patent** (10) **Patent No.:** **US D967,554 S**
(45) **Date of Patent:** **** Oct. 18, 2022**

(54) **MINERAL BRICK HOLDER**

(71) Applicant: **Outdoor Product Innovations, Inc.**,
Elyria, OH (US)

(72) Inventor: **Daniel B Reaser**, Elyria, OH (US)

(73) Assignee: **Outdoor Product Innovations, Inc.**,
Elyria, OH (US)

(**) Term: **15 Years**

(21) Appl. No.: **29/745,819**

(22) Filed: **Aug. 10, 2020**

(51) LOC (13) Cl. **30-07**

(52) U.S. Cl.

USPC **D30/121**

(58) **Field of Classification Search**

USPC D30/119, 121, 133

CPC A01K 39/0106; A01K 5/015
